United States Patent

Des. 235,770
Patented July 8, 1975

235,770

GRAIN ELEVATOR

Leo M. Becker, 1833 Swope Parkway,
Kansas City, Mo. 64130

Filed Feb. 8, 1974, Ser. No. 440,787

Term of patent 14 years

Int. Cl. D23—01

U.S. Cl. D23—2

Fig. 1.

Fig. 2.

Fig. 3.

Fig. 4.

FIG. 1 is a side elevational view of a grain elevator showing my new design;

FIG. 2 is a top plan view thereof;

FIG. 3 is an elevational view taken from one end thereof, the opposite end being a mirror image of the end shown;

FIG. 4 is a cross sectional view taken on line 4-4 of FIG. 1; and

FIG. 5 is an elevational view taken from the side opposite that shown in FIG. 1, with the center being broken away for convenience of illustration.

I claim:

The ornamental design for a grain elevator, as shown and described.
